(57) **CLAIM**

The ornamental design for an inflatable chute platform, as shown and described.

DESCRIPTION

FIG. 1 is a top view of an inflatable chute platform in accordance with the new design.

FIG. 2 is a rear left top perspective view of the inflatable chute platform depicted in FIG. 1.

FIG. 3 is a rear right top perspective view of the inflatable chute platform depicted in FIG. 1.

FIG. 4 is a bottom view of the inflatable chute platform depicted in FIG. 1.

FIG. 5 is a front left bottom perspective view of the inflatable chute platform depicted in FIG. 1; and,

FIG. 6 is a front right bottom perspective view of the inflatable chute platform depicted in FIG. 1.

Broken lines and surface shading showing various portions of the design and/or environment form no part of the claimed design.

1 Claim, 4 Drawing Sheets
